UNITED STATES PATENT OFFICE

2,062,152

PRINTING PRESS

Nelson S. Welk, Athens, Ohio, assignor to The
McBee Company, Athens, Ohio, a corporation
of Ohio

Application January 24, 1935, Serial No. 3,201

5 Claims. (Cl. 101—295)

My invention relates more particularly to those presses described in United States Patent No. 1,961,828, issued to George A. Rutkoskie, which are designed to print spots of wax carbon on sheets of paper in predetermined locations. In the patent referred to, the fact is disclosed that wax carbon must be melted to use it and it must be maintained at a critical temperature in order to produce a satisfactory job. Moreover, due to the fact that the wax carbon compound, when melted, is not tacky; it is essential that the rollers be positively driven as the frictional contact of the rollers will not cause them to rotate due to the said lack of tack.

My invention has for its object to adapt a standard Sheridan vertically reciprocating embossing press to print spots of wax carbon on sheets of paper.

My means of accomplishing the foregoing objects may be more readily understood by having reference to the accompanying drawings which are hereunto annexed and are a part of this specification, in which I show only my attachment and such fragmentary parts of the press as are necessary.

Fig. 1 is a side elevation of a press equipped with my improvement;

Fig. 2 is a diagrammatic view showing the rollers;

Fig. 3 is a top or plan view;

Fig. 4 is the opposite side elevation showing the means employed to positively drive the rollers; and

Fig. 5 is a bottom plan view showing the means employed to drive the form rollers.

Similar reference numerals refer to similar parts throughout the entire description.

As shown in the drawings, the press has standards 1 and 2 which are provided with vertical guides 3 and 4 in which is mounted an adjustable platen 5 adapted to contact the vertically reciprocating type bed 6, this being standard construction for a press of this character. In adapting the press to wax carbon work, I mount the inking mechanism on a pair of horizontal guides 7 and 8. At each end of these guides are mounted shafts 7' and 8' which carry sprocket wheels 9 and 10 which carry a chain 11 the ends of which are secured to the inking mechanism as clearly seen in Fig. 4 with the result, as the sprockets are intermittently oscillated in any suitable or convenient manner which is not shown as such mechanism forms no part of my invention, a reciprocatory motion is imparted to said inking mechanism. The operating mechanism

is so timed that the inking mechanism is stationary when it is out from under the platen 5, so that the reciprocation vertically of the type bed will cause it to press the sheet of paper against the form on the reciprocating type bed 5. The inking mechanism comprises an ink fountain 12 and an ink fountain roller 13. Electric elements 14 are mounted adjacent the ink fountain to melt the wax carbon compound therein and maintain it at the required temperature. A ductor roller 16, which intermittently contacts the ink fountain roller 13 carries the carbon to a vibrator roller 17. These rollers may be positively driven by mounting gears 13', 16' and 17' respectively on each shaft so that when the ductor roller 16 contacts either the ink fountain roller 13 or the vibrator 17, the ductor roller 16 will be positively driven. The vibrator roller 17 is also provided with an electric heating element 18. A rider composition roller 19 contacts the vibrator roller 17 and a distributor roller 20, which contacts a composition roller 21. The roller 21 carries the carbon to a large steel vibrator roller 22 which transmits it to a distributor roller 23 which delivers it to the ink cylinder 24. This cylinder 24 is preferably provided with a plurality of electric heating elements 25 to maintain the carbon at the required temperature. Form rollers 26, 27 and 28 receive the wax carbon from the ink cylinder 24 and deliver it to the form on the type bed 6. As seen in Figs. 4 and 5, a train of gearing 19', 20', 21', 22' and 23' is provided to positively drive the rollers 17, 19, 20, 21, 22 and 23.

The ink cylinder 24 is driven by a chain 29 carried by sprockets 30, 31 and 32. The latter is positively rotated by means (not shown). It will be obvious from the foregoing that not only the rollers which carry the wax carbon from the ink fountain are positively driven but that the ink cylinder 24 is also positively driven.

The ink cylinder 24 which as explained is positively driven by sprocket 30, contacts form inking rollers 26, 27, and 28, distributing the wax carbon thereon. These form inking rollers 28, 27 and 26 are positively driven by gear 40, sprocket 41, chain 42, sprocket 43, chain 44, sprocket 45, chain 46, sprocket 47, respectively, through the reciprocation of said gear 40 over rack 48. The form inking rollers 26, 27 and 28 are held yieldingly against the ink cylinder 24 by means of coil springs 26', 27' and 28' which are mounted in the form inking roller carriage 50 which slides upon the guides 7 and 8. The coil springs 26', 27' and 28', as clearly seen in 55

Figs. 4 and 5, are suitably secured to the boxes in which the shafts rotate, so as to hold the form inking rollers in contact with the inking cylinder 24. By this yielding mounting of the 5 form inking rollers, vertical movement of the same is permitted as the carriage 50 passes the ink cylinder 24. As the carriage is reciprocated, the roller 28 can be depressed and the roller 27 will then occupy the position shown in Fig. 4 10 when it is directly under the center of the ink roller 24.

It may be found desirable to locate an electric heating element adjacent rollers 20 and 21 and to mount an element 35 in the large steel 15 vibrator roller 22. It is also necessary to mount a plurality of electric heating elements 36 in the type bed 6. The operation of the press, it is believed, will be clear from the foregoing description.

20 It will also be seen that I have provided means to maintain all parts of the press which contact the wax carbon at the necessary temperature.

Having described my invention what I regard as new and desire to secure by Letters Patent is: 25 1. In a printing press, a vertical standard, a platen vertically adjustable thereon, a heated type bed, an inking mechanism comprising an ink fountain, an ink fountain roller, a ductor roller, vibrating and distributing rollers, a rotating ink cylinder, form rollers which contact said ink cylinder, means to positively drive all of said rollers, means to reciprocate said form rollers across the said type bed, said means comprising a pair of horizontal guides on which said 30 form rollers are slidable, a sprocket at each end thereof, a chain on said sprockets, said form rollers being secured to said chain whereby its movement will move said form rollers.

2. In a printing press, a vertical standard, a platen vertically adjustable thereon, a heated type bed, an inking mechanism comprising an ink fountain, an ink fountain roller, a ductor roller, vibrating and distributing rollers, a rotating ink cylinder, form rollers which contact said 45 ink cylinder, a carriage in which said form rollers are mounted, means mounted in said carriage to hold said rollers yieldingly in contact with said ink cylinder when abutting said cylinder, means to positively drive all said rollers, and 50 means to reciprocate said carriage and form inking rollers across said type bed.

3. In a printing press, a vertical standard, a platen vertically adjustable thereon, a heated type bed, an inking mechanism comprising an

ink fountain, an ink fountain roller, a ductor roller, vibrating and distributing rollers, a rotating ink cylinder, form inking rollers, shafts for said rollers, a carriage in which said shafts are mounted, coil springs mounted in said carriage which hold said form inking rollers in contact with said ink cylinder when abutting said cylinder, means to positively drive all of said rollers, guides on which said carriage slides, means to reciprocate said form inking rollers 10 across said type bed, and means to heat all parts of the press which contact the wax carbon. 5

4. In a printing press, a vertical standard, a platen vertically adjustable thereon, a heated type bed, an inking mechanism comprising an ink fountain, an ink fountain roller, a ductor roller, vibrating and distributing rollers, a rotating ink cylinder, a train of gears to drive all of said rollers, a plurality of form inking rollers, shafts therefor, a carriage in which the ends of 20 said shafts are mounted, springs in said carriage which yieldingly hold said form inking rollers against said ink cylinder, a shaft the ends of which are rotatably mounted in said carriage, a plurality of sprockets on said shaft, sprockets 25 on each of the form inking roller shafts, chains on said sprockets to drive said form inking rollers on said sprockets, means to rotate the shaft carrying the plurality of sprockets, means to reciprocate said carriage whereby the form inking 30 rollers will be moved across the type bed, and means to heat all parts of the press which contact said wax carbon. 35

5. In a printing press, a vertical standard, a platen vertically adjustable thereon, a heated type bed, an inking mechanism comprising an ink fountain, an ink fountain roller, a ductor roller, vibrating and distributing rollers, a rotating ink cylinder, a plurality of form inking rollers which contact said ink cylinder, means 40 to positively drive all of said rollers, shafts for said form rollers, a carriage in which the ends of said shafts are mounted, means to reciprocate said carriage across said type bed, said means comprising a pair of horizontal guides on which 45 said carriage is slidable, a shaft at each end of said guides, sprockets on said shafts, chains or said sprockets, said carriage being secured to said chains whereby movement thereof will move said carriage, and spring means mounted in 50 said carriage to hold said form inking rollers in yielding contact with the cylinder when abutting said cylinder.

NELSON S. WELK.
